UNITED STATES PATENT OFFICE.

GEORGE E. EVANS AND WILLIAM F. EVANS, OF MOLINE, ILLINOIS, ASSIGNORS TO THE GEORGE EVANS CORPORATION, OF MOLINE, ILLINOIS, A CORPORATION OF ILLINOIS.

HEATING FURNACE.

Application filed June 20, 1927. Serial No. 199,919.

The present invention relates to heating furnaces and has particular reference to hot air furnaces of the type employed for household heating, although the novel features of 5 the invention may be embodied in other types of heating units, such, for example, as in industrial furnaces for heating gases etc.

The principal aim of the invention is to provide a heating furnace wherein the heating 10 passages are built up of sheet metal sections of improved form and construction. By virtue of these sheet metal sections the area of heat transfer surface for a given size of furnace is greatly increased; the walls 15 through which this heat transfer is effected are of relatively small sectional thickness, so that the furnace is quickly brought up to heating temperature; the alternate expansions and contractions of the heating sections 20 are readily accommodated by the flexibility of the sheet metal walls, which is of particular advantage when the furnace is being fired by an intermittently operating oil burner; and the entire furnace is made relatively light in weight, and is produced at 25 low cost.

Referring to the accompanying drawings wherein we have illustrated a preferred embodiment of our invention:

30 Figure 1 is a vertical longitudinal sectional view through the furnace.

Fig. 2 is a horizontal view, partly in elevation and partly in section, showing the arrangement of the heating sections.

35 Fig. 3 is a vertical transverse sectional view taken on the plane of the line 3—3 of Figure 1.

Fig. 4 is a fragmentary perspective view 40 of one of the sections.

Fig. 5 is a fragmentary sectional view 45 illustrating the manner of connecting the ends of the sections, and

Fig. 6 is a detail sectional view illustrating a modified construction.

50 The furnace is preferably of rectangular form, and is enclosed in a housing 10 which may be suitably insulated against heat loss. This housing may be of unitary construction, or it may be sectionalized into a plurality of walls or panels adapted to be joined together. In the construction shown, the front and rear walls 11—11' and the end walls 12 are formed as an integral rectangular shell. The top of such shell is open, and 55 is adapted to be closed by a removable cover

plate 13 which is bolted to the flanged upper edge of the shelf 10. Rising from the cover plate 13 is a hot air manifold 14, which may consist of a suitable sheet metal housing or shell secured to an upwardly extending 60 flange 15 projecting from the cover plate 13. Branching from the top of the manifold 14 are one or more hot air conduits 16 which serve to conduct the heated air to different parts of the house or building. 65

Extending transversely of the furnace, intermediate the ends thereof, is a fire box 17. Such fire box preferably extends down substantially to the floor, and the lower portion thereof is defined between side walls 18 composed of fire brick, or fire clay reinforced by side plates 19. The upper portion of such fire box or combustion chamber is defined between the ends of right and left banks of heating sections 21 which extend laterally 70 from this combustion chamber toward the ends of the furnace. The top of the chamber is closed off from the hot air manifold 14 by a plate 22 which is secured to the tops of the sections and extends the full length 75 of the chamber. Provision may be made for burning coal, oil, or gas in the fire box, the conduit 23 entering the front end thereof being representative of an oil burner conduit. It is opportune to remark at this point that 80 the construction shown is what we regard as a large or double unit, characterized by an intermediately located fire box having heating sections extending laterally from each side thereof, but if desired, smaller units can 85 be constructed with a single bank of sections extending from the end or side of the fire box.

The products of combustion pass laterally 90 in each direction through the banks of sections 21—21 towards the ends of the furnace. In their passage through these sections, the products of combustion are caused to flow through tortuous or sinuated passages which 95 lie in immediate proximity to vertically extending air passages for effecting an efficient transfer of heat, all of which will appear in the subsequent description of the sections. The products of combustion issue 100 from the ends of the sections into discharge chambers 24 defined between the end walls of the housing and the faces of the banks of sections 21—21. The tops of both of said chambers are closed by the cover plate 13, and the bottoms thereof are closed by plate 110

portions 25 extending inwardly from the furnace housing at a point spaced upwardly from the bottom of the housing. The areas defined below these inwardly extending plate 5 portions 25, and below the bottoms of the sections 21, constitute cold air chambers 26 where the air is admitted to the furnace for passing up between the heating sections. Formed in each of the plate portions 25—25 10 are elongated openings 27 which communicate with exhaust conduits 28. The latter convey the exhaust gases to a stack conduit 29 which may extend from the back or ends of the furnace, as desired. In the arrangement shown, said stack conduit extends upwardly from the rear wall 11' of the furnace housing and the two conduits 28 extend diagonally back to such rear wall where they both open into the stack conduit. At the 15 point where the conduits 28 pass out through the housing, an inclined protecting wall 20 of fire clay or brick is built up to cover the conduits 28 and protect them from the burner flame. The air to be heated is admitted to the lower chamber areas 26 20 through openings 31 formed in one of the walls of the housing, such as the rear wall, and these openings may communicate with a manifold or conduits leading to any point 25 from which it is desired to draw the air.

The plate portions 25 form parts of open frame structures which support the heating sections 21 above the air chambers 26. Such frames may be cast in unitary form or may 30 consist of suitable angle bars 32 and 33 secured to the front and rear walls of the housing and to the side plates 19 of the fire box.

Referring now to the manner of constructing the heating sections, it will be observed 40 from Fig. 4 that each section is composed of two sheet metal side walls 34^a and 34^b. Although we find it preferable to make these two side walls from separate 45 sheets, as by joining the edges of these sheets along the upper and lower edges of the section, it will be understood that such side walls might consist of two halves of a single sheet folded along a 50 median line. Prior to the joining of the edges of such sheets, corrugations or indentations are formed therein to produce alternating peaks 35 and valleys 36. Such corrugations or indentations may be formed in 55 the plates either by rolling, stamping, or in any other preferred manner, and may be of V-shaped cross section as shown, or of gradually rounded curvature, although we find the approximate sectional formation shown 60 to be preferred for best results. The corrugations extend crosswise of the sheets, so that they will be disposed vertically in the finished section, and the upper and lower ends of each corrugation terminate short of 65 the edges of the plate, merging on gradually

rounded curves 37 into the plane of the sheet. The flat edge portions lying beyond the corrugations along the upper and lower edges of the plate constitute joining flanges 38^a and 38^b. Said flanges are preferably joined together by welding, performed either by an oxy-acetylene flame, or electrically, the weld being indicated at 39. It will be observed from Fig. 5 that in the finished section the peaks 35 of one plate match with 70 the valleys 36 of the opposite plate, and that these peak and valley portions are spaced from each other to define a zig-zag or simulated passageway 41 of substantially uniform 75 cross-sectional area extending throughout the entire length of the section. Such passageway constitutes a flue duct for conducting the hot gases through the heating section, opening at one end into the combustion chamber 17 and at the other end into the 80 exhaust chamber 24.

The sections thus formed are grouped in banks or nests, so arranged as to define vertically extending air passages 42 extending up between adjacent sections. Preferably the sections are so arranged that the peak portions 35 of one section contact with or lie in immediate proximity to the peak portions of the next adjacent section. In such arrangement the air passages 42 are 90 defined between the matching valley portions of adjacent sections and hence are of square or diamond shaped cross section, depending upon the specific form of the corrugations. While this is the preferred arrangement, it will be evident that the sections might be grouped with the peak portions 35 of one section matching with the valley portions 36 of the next adjacent section, but spaced therefrom so that the upwardly extending air passage 42 would be 100 in the shape of a continuous passage of simulated form extending throughout the length of the bank of sections.

The end faces of each bank of sections 110 are closed off in the manner shown in Fig. 5, or in accordance with the modified construction shown in Fig. 6, whereby the air spaces between adjacent sections are sealed from the ends of the sections, leaving only 115 the flue passages 41 opening outwardly from the ends of the sections. It will be observed that when the sections are grouped with the peaks of one section lying opposite the peaks of the next adjacent section, the flue passages 41 of two of these sections will open from the end of the bank in immediate 120 proximity to each other, and the flue passages of the next two sections will open from the end of the bank, also in immediate 125 proximity to each other, but spaced from the first pair of flue passages by the width of one of the air passages 42. The opposite walls 34^a—34^b of the first mentioned pair of sections contact back to back at the end 130

of the bank and are welded together along their entire contacting portions, as indicated at 44. The intervening space between this pair of adjacent flue passages and the 5 pair of the next adjacent flue passages is sealed by a closure flange 45 which is bent at right angles to one of the sections to extend over and engage with the opposite wall of the next adjacent section. The edge of 10 this flange is welded to the contacting edge of the latter section along the line indicated at 46. The above described manner of joining adjacent sections is continued across the entire end face of the bank, and is duplicated 15 at the other ends of the sections. Thus, while the situated flue passages are open at the ends of the sections, the air spaces intermediate the sections are closed off from said ends.

20 In the modified construction shown in Fig. 6, the intervening space between pairs of flue passages is closed by extending two flanges 47—47 from each of the adjacent sections at this point, and bending the edges of 25 said flanges forwardly for welding along the line 48.

After the sections have been joined together in the manner described, the two banks thereof are placed within the housing 30 10, where they rest on the frame bars 25, 32 and 33. The lower edges of each bank may be suitably secured to said frame bars to form an air-tight closure between the edges of the bank or group of sections and 35 said bars. The front and rear sections of each bank are also joined to the front and rear walls of the housing. One manner of accomplishing this is to bend the projecting flange portions 45 of such front and rear sections at a right angle, as indicated 40 at 45', and securing said bent portions to the housing. Where these flanges 45 do not occur between the outermost sections and the housing, suitable angle strips, similar to the bent portions 45', may be secured to said sections and to the housing. For closing off the openings which occur at the upper and lower edges of the sections at the points where the corrugations 35—36 curve back 45 into the planes of their respective sheets, we provide closure members in the form of angle bars or plates 51 which extend across the ends of each group of sections at the upper and lower edges thereof. These 50 closure members are preferably welded to the edges of the sections and to the closure flanges 45 so as to seal the air spaces at the upper and lower edges of the sections.

It will be seen from the foregoing that 60 the products of combustion will pass laterally in each direction from the combustion chamber 17 through the horizontally extending flue passages 41 of the sections and will discharge into the end chambers 24. 65 From these chambers the spent gases are

conducted downwardly through the conduits 28 to the stack 29, this providing in effect a down draft for the flue gases. The relatively cold air entering the lower chambers 26 will pass upwardly through the air passages 42 between adjacent sections, where such air will be heated, the same then discharging into the manifold 14 for passage through the conduits 16 to the different parts of the house. The multiplicity of flue 70 75 passages 41 and air passages 42 afford an extensive area of heat exchange surfaces, tending to a high efficiency of the furnace. Whatever temperatures are present in the exhaust gases being conducted through the 80 conduits 28 are also effective for heating the air in the lower air chambers 26. Obviously the sheet metal sections possess an inherent flexibility which accommodates a wide range 85 of expansion and contraction.

While the construction above described embodies what we consider to be the preferred form of the invention, it will be understood that such is merely exemplary, and that different changes and rearrangements may be made therein without departing 90 from the invention.

What we claim as our invention and desire to secure by Letters Patent, is—

1. A heating furnace having a heating 95 section comprising pairs of spaced parallel walls, said walls being formed of similar corrugated plates with the corrugations of one plate extending in the same direction as the corrugations of the other plate, thereby 100 defining a passage through which the gases advance in a sheet of uniform cross section, the adjacent pairs of walls being spaced to form a plurality of noncommunicating air passages between them. 105

2. A heating furnace having two groups of heating sections extending laterally from opposite sides of a fire box, each of said sections comprising a plurality of pairs of corrugated metal plates with the corrugations of one plate parallel to the corrugations of the other plate, thereby defining a 110 passage through which the gases advance in a sheet of uniform cross section, said pairs of corrugated plates defining sinuous 115 lateral flue passages interiorly, noncommunicating air passages exteriorly, means for admitting hot gases of combustion to said lateral passages from said fire box, and means for admitting air to be heated at the 120 bottom of said air passages.

3. A heating furnace comprising a fire box, a group of heating sections, each of said sections comprising a pair of spaced similarly corrugated plates a uniform distance 125 apart throughout the entire areas of the plates, said corrugations being placed so as to define a sinuous flue passage within parallel curved walls, said sections being spaced with respect to each other to define air pas- 130

- sages, said first passage having openings for conduction of the hot gases of combustion, and said second passage having openings for admission of air to be heated.
- 5 4. A heating furnace comprising a heating section formed of a plurality of similarly corrugated metal plates, pairs of said plates defining similar sinuous flue passages, said passages having a uniform cross-section throughout said walls exteriorly defining a plurality of non-communicating air passages, means for admitting the hot gases of combustion to said flue passages, means for admitting air to be heated to said air passages, the ends of said corrugations terminating short of each plate to form joining flanges along the edges of said plates, said flanges contacting with each other and being welded together, intervening members 15 between said lateral passages to prevent passage of flue gases into the air passages, and means for joining said intervening members to said metal plates.
5. In an air heating furnace, a plurality of spaced pairs of corrugated plates, each pair defining a flue passageway, the plates of adjacent pairs defining a flue passageway extending at right angles to the first mentioned flue passageway, means for passing gases of combustion through one of said passageways, and means for passing air through the other passageway. 25
6. In an air heating furnace, a plurality of spaced pairs of corrugated plates, each pair defining a flue passageway of uniform cross sectional area, the plates of adjacent pairs being joined together to define a plurality of spaced parallel passageways, extending at right angles to the first mentioned flue passageway, means for passing gases of combustion through one of said passageways, and means for passing air through the other passageway. 30 35
